UNITED STATES PATENT OFFICE.

EDWARD F. ASTLEY, OF CHICAGO, ILLINOIS, ASSIGNOR TO HUMBOLDT M. SEYER, OF CHICAGO, ILLINOIS.

BRUSH.

Application filed March 7, 1927. Serial No. 173,380.

This invention relates to brushes and has for its object to provide a new and improved device of this description.

The invention has a further object to provide a simple and useful brush arranged so that the liquid to be applied by the brush will be continuously supplied thereto.

The invention has as a further object to provide a brush having an applying member to which the liquid is continuously applied with means for holding the applying member in position so that it can be easily removed and replaced.

The invention has further objects which are more particularly pointed out in the accompanying description.

Referring now to the drawings, Fig. 1 is a view of one form of brush embodying the invention.

Fig. 2 is a longitudinal, sectional view through the device shown in Fig. 1.

Fig. 3 is a sectional view taken on line 3—3 of Fig. 2.

Fig. 4 is a view of the removable piece for the applying member.

Fig. 5 is a view of the outer piece for the applying member before it is connected thereto.

Fig. 6 is a view of the applying member with the outer piece in position, parts being broken away.

Like numerals refer to like parts throughout the several figures.

In the construction illustrated, I provide a handle made up of members 1 and 2, said members being hollow so as to form a liquid reservoir and being removably connected together by means of the screw thread 3. The member 2 is provided at its end with an opening 4, an applying member 5 is used to apply the material to the surface upon which it is desired to utilize it.

The applying member is provided with a ferrule 6 connected with one end thereof and projecting beyond the applying member, the projecting portion being hollow. This construction is shown in Fig. 6. An outer piece 7 extends around a portion of the applying member and ferrule, as shown in Figs. 2 and 6. This outer piece is provided with one or more openings 8 through which the liquid from the handle passes to the applying member. Since the outer piece 7 extends around the end of the ferrule 6, it will be noted that there is a space 9 between the applying mem-

ber and the outer piece 7 so that the liquid will flow through the openings 8 along this space and thus be properly supplied to the applying member.

The outer piece 7 is provided with a projecting ring 10 near its lower end, this ring being made by bending the material outwardly thus forming a groove 11 extending around the applying member. This groove is filled with the liquid and holds this liquid around the brush so as to form a seal. When the device is not in use, this seal acts to exclude the air from the interior of the brush handle, as it makes an air-tight connection between the applying member and the outer piece 7.

The ring 10, when the applying member is in position, engages the inwardly projecting portion 11^a on the handle member 2 located at the opening 4, and seals this opening and also acts as a stop to prevent the outward movement of the applying member.

As herein shown, I provide a removable, fastening piece 12 bent into the form of a loop, adapted to be received into the hollow end of the ferrule 6. This fastening piece is provided with engaging projections 13 and 14 which engage a fixed part so as to limit the inward movement of the applying member.

In the construction shown, these engaging projections engage the end 15 of the member 1 of the handle, as shown in Fig. 2. The ends of the fastening piece project beyond the engaging projections 13 and 14 as shown at 14^a. The projections 13 and 14 are preferably made by bending a portion of the material laterally as shown in Fig. 4.

In the use of the device, the two sections of the handle are disconnected and the applying member is inserted in the member 2 so that the applying member 5 projects through the opening 4 therein as shown in Fig. 2. The looped end of the fastening piece 12 is inserted in the hollow end of the ferrule 6, as shown in Fig. 2. The liquid is placed in the receptacle in the handle and the two parts of the handle are then fastened together. The engaging projections 13 and 14 then engage the end 15 of the section 1 and the stop or ring 11^a engages the inwardly projecting portion 11^a of the handle section 2.

The screwing of the two sections of the handle together causes the ring 10 to press tightly against the projecting portion 11^a, so as to

make a tight connection and prevent leakage of the liquid from the handle.

In the use of the device, the liquid is continuously supplied to the applying member 5 through the opening 8 in the outer piece 7. As the applying member is used, it will be moved slightly away from the end of the outer piece 7, permitting the flow of the liquid through the openings 8 and the space 9 to the portion 10 of the applying member projecting beyond the handle.

It will thus be seen that the liquid will be continuously applied to the applying member and the parts are arranged so that this supply will be in the proper quantity at all times. When the device is not in use, the liquid seals the groove 11 extending about the applying member and acts as an air-tight seal. If the brush is not used for a time and then is again 20 used, this liquid in the groove 11 is immediately available to supply the applying member and the groove is kept continuously sealed as the applying member is used.

When the applying member becomes inefficient by being worn or for any other reason, or when it is desired to change or renew the applying member, the two sections of the handle are disconnected. The ends 14^a of the fastening piece 12 are then grasped between the 30 thumb and finger and pressed towards each other and the fastening piece removed from the ferrule 6. The ferrule 6, outer piece 7 and applying member 5 are then removed. A new applying member and ferrule and outer piece 35 may then be inserted into the section 2 of the handle and the fastening piece 12 placed in the hollow end of the ferrule 6 and the two parts of the handle connected.

It will thus be seen that by means of this

connection, the applying member may be 40 easily removed and replaced. When the applying member becomes worn or inefficient, it can be thrown away and a new applying member inserted in the handle.

I claim:

1. A brush comprising an applying-member, a tubular ferrule connected with the upper portion of said applying-member, an outer piece extending around a portion of said ferrule and applying-member and provided with 50 an opening intermediate its end, a stop on said outer piece near one end thereof, and a fastening piece bent in the form of a loop, the loop-portion projecting into the hollow of 55 said ferrule, said fastening piece having laterally extending engaging pieces, said engaging pieces limiting the inward movement of the fastening piece into the hollow of said ferrule.

2. A fountain-brush comprising a hollow 60 handle having two hollow sections removably connected together, one of said sections comprising a tip-member provided at its free extremity with an opening and with an annular seat encircling said opening, a brush extending through said opening and equipped at its inner end with a ferrule, an outer tubular member connected with the lower end of said ferrule and having an external bead engaging 65 said seat, said outer tubular member having an opening through its wall for admitting liquid to the brush; and means for anchoring said ferrule in the tip-portion of the handle with 70 said bead seated on said annular seat.

Signed at Chicago county of Cook and 75 State of Illinois, this 19th day of February, 1927.

EDWARD F. ASTLEY.
